SOCKET AND BASE FOR TRANSLATING DEVICES

Filed Jan. 12, 1926

Fig. 1

Fig. 2

The diagram shows a circular component with several labeled parts and mounting features. At the top center is a label '31'. The circular area contains labels '38', '39', '36', '35', and '38'. Surrounding the circle are labels '30', '37', '40', and '39'. There are four rectangular cutouts with mounting holes, each labeled '37', '40', and '39' respectively. The entire assembly is shown with a dashed rectangular border.

UNITED STATES PATENT OFFICE.

HARRY SHOEMAKER, OF JERSEY CITY, NEW JERSEY, ASSIGNOR, BY MESNE ASSIGNMENTS, TO ELKON WORKS, INC., A CORPORATION OF NEW JERSEY.

SOCKET AND BASE FOR TRANSLATING DEVICES.

Application filed January 12, 1926. Serial No. 80,777.

This invention relates to sockets and bases for translating devices, and particularly to those adapted for use with replaceable translating devices having a so-called valve action.

The object of the invention generally is to provide an improved construction and arrangement of parts which is efficient, economical and readily manufactured.

10 More specifically an object of the invention is to provide a socket and base whereby translating devices such as asymmetric cells of the dry surface-contact variety may be easily inserted and withdrawn from electrical systems using the same without impairing its contact connections therewith or otherwise interfering with the operating characteristics of the devices.

Other objects of the invention will be in 20 part be obvious and will in part appear hereinafter.

The invention accordingly comprises the features of construction, combinations of elements, and arrangement of parts, which will 25 be exemplified in the constructions herein-after set forth and the scope of the application of which will be indicated in the claims.

For a fuller understanding of the nature 30 and objects of the invention reference should be had to the following detailed description taken in connection with the accompanying drawing, in which:

Figure 1 is a view showing a side elevation of a typical translating device having asymmetric cells of the dry surface-contact variety provided with a base in accordance with the invention;

Fig. 2 is a view showing in elevation a 40 translating device of the character specified removed from its socket, the plane of the view being taken at right angles to that of Fig. 1;

Fig. 3 is a view, partly in section and 45 partly in plan, arranged to show the adaptation of the base device so as to fit the socket in accordance with the invention; and

Fig. 4 is a top plan view of the socket with the translating device removed.

50 Referring now particularly to the drawing, 10 denotes a translating device shown by way of example as having a plurality of asymmetric couples 11 of the dry surface-contact variety, such as disclosed in the co-pending application for Letters Patent of

the United States filed by Samuel Ruben on November 18, 1924, Serial No. 750,939. The couples thus provided are arranged to have a so-called "valve" or rectifying action and are preferably disposed symmetrically 60 on each side of a central conducting plate 12; the nut and bolt, shown at 13, serving to retain the couples properly in place. The symmetrical arrangement here illustrated is adapted to utilize both halves of the alternating current; but while the arrangement is convenient, it is by no means essential to the practice of the present invention. 65

In this arrangement, conducting end plates 14 are applied to the device which 70 have the same polarity but is the opposite of that of plate 12. These end plates are conveniently extended as indicated at 15 and have upset portions 16 which are adapted to support the device as a unit upon 75 the insulating disc 17, the latter serving as the base proper for the rectifying unit here provided. The conducting portions 16 thus secured to the base 17 are adapted to be connected to one terminal of the direct current 80 circuit, since they have the same polarity. To this end the contacting portions 16 have extensions 18 which extend beyond the base to engage with the socket in the manner 85 hereinafter described.

The insulating base, as indicated in Figs. 1 and 2, is adapted to be removably disposed in a socket 30, and when inserted, to make the necessary contacts with the conductors of the electrical system to which it is 90 applied. The base 17 is accordingly provided with additional contact elements connected to the various portions of the rectifying device. In accordance with this provision, the base is shown in Fig. 2 as having 95 three depending contact elements 21, 22 and 23, which project through the base 17, but are cut short on the upper side. They may be made in tubular form or otherwise provided with countersunk openings as indicated at 24 (see Fig. 3), as this feature facilitates the insertion of the conductors 25, 26 and 27 which are provided to make contact with the elements of the asymmetric couples 11. For example the conductors 25 and 27 are secured respectively in contact 100 elements 21 and 23 and are connected to intermediate points in the group of asymmetric couples which are at opposite sides 105 of the central plate 12, while the conductor 110

26, which leads from the plate 12, makes contact with the middle contact element 22.

A rectifying unit provided with a base as shown at 17 in Fig. 2, is adapted to be 5 removably supported in a socket which has conducting means disposed to engage in bayonet fashion with the projections 18. This is conveniently accomplished by the arrangement here shown, where a conducting collar 30 is mounted on an insulating plaque of other suitable support 31. The conducting collar, thus provided, has up-standing lugs 32 formed with slots on opposite sides into which the projections 18 10 may be slid for bayonet engagement with the conducting collar 30 by a partial rotation.

The collar 30 is arranged to be conductively connected with the conducting terminal 20 clip 33 disposed on the underside of the insulating plaque 31. It is adapted to provide a suitable terminal through which the direct current circuit is connected to the translating device. In order to provide similar terminals for the other circuit connections, the insulating plaque 31 supports additional contact members, preferably of the spring variety, which make suitable contact with the contact elements 21, 22 and 23. 25 This may be conveniently accomplished without cutting away the whole of the insulating plaque 31 within the conducting collar 30, thereby providing a strong and convenient arrangement. Accordingly the insulating plaque 31 has a perforation 35 centrally disposed within the conducting collar to accommodate the centrally disposed contact element 22 projecting from the base. Disposed under this perforation is a spring contact member 36 which has a terminal clip 37 adapted to serve as the other terminal of the direct current circuit. In like manner elongated perforations 38 are provided in the insulating plaque on diametrically opposite 45 sides of the central perforation 35. These elongated perforations admit the insertion of the depending contact elements 21 and 23 to make contact respectively with the spring-contact members 39 which have terminal 50 clips 40 extending at opposite sides of the insulating plaque 31. The perforations 38 are sufficiently elongated to permit the inserted contact elements 21 and 23 to turn through an arc of sufficient magnitude to 55 permit the partial rotation of the rectifier unit to a position where the projections 18 clear the lugs 32 so that the rectifying unit 10 may be withdrawn or replaced.

By this invention, it will be seen, that a 60 rectifying or like translating device may be arranged in convenient units on a base which is adapted to be removably inserted in a socket where it makes contact with the conductors of circuits in an electrical system 65 such as is employed in the rectification of

alternating currents. In such a system, for example, the clips 40 are adapted to serve as the alternating current input terminals, while the clips 33 and 37 are adapted to serve as the terminals for the direct current 70 output circuit.

Since certain changes may be made in the above construction and different embodiments of the invention could be made without departing from the scope thereof, it is 75 intended that all matter contained in the above description or shown in the accompanying drawing shall be interpreted as illustrative and not in a limiting sense.

Having described my invention, what I 80 claim as new and desire to secure by Letters Patent is:

1. In combination, a socket having a conducting collar provided with lugs for bayonet engagement, and having a plurality of 85 contact terminals associated therewith, one of said terminals being electrically connected to said collar, an insulating base adapted to fit within said conducting collar and provided with contacting elements disposed to 90 engage respectively with the remaining contact terminals associated with said socket, conducting supporting members mounted on said base and provided with projections adapted to make bayonet engagement with the lugs on said conducting collar and thereby afford electrical engagement for one terminal of an electric circuit, and a translating device having an asymmetric couple of the dry surface contact variety, said couple being operatively connected to said contacting elements. 95

2. In combination, a socket comprising an insulating plate and a conducting collar and having a plurality of contact terminals associated therewith, one of said terminals being electrically connected to said collar the remaining terminals being of the spring contact variety, an insulating base provided with projecting contact elements disposed to 100 engage respectively with the spring contact terminals in said socket, conducting supporting members mounted on said base and adapted to make contact with said conducting collar, and a rectifying device of the dry surface contact variety supported on said base by said conducting supporting member and having operative electrical connections to said contacting elements, said base being adapted to be removably secured in said socket and having one contacting element disposed to engage with said collar. 110

3. In combination, a socket comprising an insulating plate and a conducting collar having slots for bayonet engagement and provided with a plurality of contact terminals, one of said terminals being electrically connected to said collar, the remaining terminals being of the spring contact variety, an insulating base adapted to fit within said 120 125 130

collar and provided with downwardly projecting contacting elements disposed to engage with the spring contact terminals of said socket, conducting supporting members 5 on said base, and adapted to engage with said bayonet slots, and a rectifying unit mounted on said base comprising a plurality of asymmetric cells of the dry surface-con- tact variety electrically connected as the arms of a four-sided bridge and having 10 electrical connections to said contacting elements, said base having one contacting element disposed to engage with said collar.

In testimony whereof I affix my signature.

HARRY SHOEMAKER.
